CLAIM

We claim the ornamental design for a laboratory instrument housing, as shown and described.

DESCRIPTION

FIG. 1 is a left-front perspective view of a laboratory instrument housing.

FIG. 2 is a right-front perspective view.

FIG. 3 is a front view.

FIG. 4 is a back view.

FIG. 5 is a left side view.

FIG. 6 is a right side view.

FIG. 7 is a bottom view.

FIG. 8 is a right perspective view with a drawer in an open position.

FIG. 9 is a left perspective view with the door shown in the open position; and,

FIG. 10 is a top view.

The broken lines shown in the figures represent portions of the laboratory instrument housing that form no part of the claimed design.
